ELIHU C. WILSON, OF LOS ANGELES, CALIFORNIA

WELL SCREEN

Application filed May 12, 1925. Serial No. 29,663.

This invention has to do with strainers or screens for deep wells and the like, such screens being generally in the nature of perforated lengths of well pipe or casing provided in the pipe string at or near the well bottom.

By reason of the perforations provided in the screen lengths and the resulting comparative weakness thereof, it often happens that the screens are collapsed or sheared by the action of offset lateral forces as the surrounding earth strata shift. The resulting losses incident to making necessary repairs and replacements are too well known to those skilled in the art to call for comment here.

It is therefore among the objects of the present invention to provide a well screen which is so constructed that it is capable of effectively resisting the collapsing and shearing forces imposed upon it.

It might be supposed that the natural solution would be merely to use pipe of increased thickness; however such an expedient does not satisfy both for the economic reason that it calls for special pipe and for the reason that it is impracticable to perforate extra heavy pipe in the manner necessary to provide efficient screening. The perforations must be relatively fine and in great number, and tools of the requisite size to make perforations cannot be made sufficiently sturdy to withstand usage on extra heavy pipe. And furthermore the use of extra heavy pipe necessarily decreases the inside diameter of the pipe that can be put down a given size drill hole.

Therefore to secure the requisite weight and strength the present invention contemplates the use of a double walled pipe; for instance the screen may be made up of two pipes or sections of pipes, one nested within the other, either or both of which may be of standard thickness. These two pipes have registering perforations and preferably the outer pipe is provided with fine straining openings while the inner pipe has a comparatively large perforation. While I speak of the two walls as being two pipes, it will be apparent from what is said hereinafter that so far as the invention in this application is concerned it is

broadly immaterial how the outer wall is put around the inner wall. While I describe the outer wall as a pipe which will be slipped over the inner pipe, yet it will be apparent that the outer wall may be wrapped about the inner pipe; or in other words it might be said that the outer pipe may be formed immediately in place around the inner pipe. But however the outer pipe or wall is placed upon the inner one, it is preferred that the two walls be tightly nested; so that the two walls strengthen each other in a manner which they would not do if the outer wall were spaced from the inner wall.

The following detailed specification and the claims appended to this application are directed particularly to a specific form of double-walled strainer in which fine straining openings in one or the other wall, preferably the outer wall, are formed in a plug or button inserted in a comparatively large opening in that wall and preferably held in place by a bearing against the other wall. Other forms of straining openings and other forms of construction for reinforcing and strengthening the pipe (whether the pipe be used as a well strainer or not) are described and claimed in other co-pending applications which are in part divisional of this present application. Said co-pending applications are identified as follows:

Well pipe and screen, Serial Number 131,354, filed August 25, 1926; and,

Well pipe and screen, Serial Number 131,355, filed August 25, 1926.

One of the advantages of the present invention is that the several parts which go to make up the screen may be formed before assembly; so that the fine screening openings may be formed by whatever process, tools or machinery may be most adaptable, and the larger openings through the two pipe walls may likewise be most easily and economically made. Another advantage lies in the great strength attained without either decreasing the inside diameter of the screen or objectionably increasing the outside diameter. In fact the outside diameter need be no larger than that of the coupling covers provided between adjacent lengths of ordinary pipe.

And thus a screen constructed in accordance with this invention will have a maximum internal diameter, having great strength, and also will not necessitate the drilling of an oversize well hole.

For the purpose of setting forth in detail certain specific and illustrative forms of screen embodying the invention I now refer to the accompanying drawings, in which:

Fig. 1 is a side elevation of a screen made in accordance with the invention, shown partly in section and part of the outside wall being broken away to show the inner wall:

Fig. 2 is an enlarged section on line 2-2 of Fig. 1;

Fig. 3 is a front elevation of the screening element shown in Fig. 2;

Fig. 4 is a view similar to Fig. 2 but showing how the screening button may be inserted in the outer pipe from the outside;

Fig. 5 is a view similar to Fig. 4 but showing the button secured in place;

Fig. 6 shows another type of screening button being inserted into the outer pipe;

Fig. 7 is a view similar to Fig. 6 but showing the button secured in place; and

Fig. 8 shows how the screening element similar to those illustrated in Figs. 2 to 7 inclusive may be inserted in the wall of the inner pipe and held in position by the overhang of the outer pipe.

It is usually desirable, though not necessary, that the screening perforations be of larger size at the inside of the screen than at the outside. Since the screen embodying this invention is made up of two or more pipes, walls or elements which may be perforated before assembly, it is a matter of ease to secure the desired effect of varying perforations by properly proportioning the holes in the several elements of the screen, in addition to making the holes in the outer element narrower or of smaller diameter at their outside than at their inside.

While the screen will first be described as being made up of a plurality of end to end outer pipes on a single inner pipe, it will be understood that it lies within the scope of the invention to space the outer pipes apart or to provide a single outer pipe extending over the entire perforated parts of the inner pipe.

In Figs. 1 and 2 numerals 10, 10^a and 10^b designate lengths of inner pipes secured together by coupling collars 11 in the usual manner. Before the outer casing 12 is affixed thereto the pipes 10 are punched or drilled to provide relatively large perforations 13. The outer pipes or casings 12 may be made up of a single length between collars 11 or of several lengths abutting endwise against each other and abutting collars 11 endwise. These several lengths or sections 12 may be, if desired, butt-welded together at their ends and furthermore they may be welded to collars 11 if desired. They may preferably be tightly

fitted upon inner pipe 10 by being shrunk upon that pipe; or, as I have indicated before, the sections 12 may be actually formed around pipe 10 by bending the sheet of which the sections 12 are made up and then welding the seam (see 12^a in Fig. 1) and thereby forming the outer pipe wall. And if desired the sections 12 may be spot-welded to the inner pipe at various points.

Putting the outer pipe 12 on in short sections facilitates the shrinking operations, as will be well understood; but when the sections are then welded end to end they become in effect a single length extending between collars 11.

The outer pipe 12 is also perforated with perforations 14 before it is put in place upon the inner pipe. As shown at Fig. 2 these perforations 14 are of large diameter like perforations 13 of the inner pipe, and as shown in that figure the perforation or bore 14 tapers towards the outside; so that the conical or tapering button 17 may be fitted into tapered bore 14 from the inside of pipe 12 and then when pipe 12 is placed upon pipe 10 the button will seat at 20 on the outer face of pipe 10 where that face of the inner pipe overhangs the larger end of opening 14 in the outer pipe. These straining buttons may have straining apertures of any shape or size desired. For instance as shown in Fig. 3 they may be in the form of narrow slots 18.

If the outer pipe or wall is made of several sections as illustrated in Fig. 1 and the several sections are welded end to end or also welded to collars 11, it will be seen that a complete double walled assembly of the maximum strength is provided, to resist shearing, torsional or crushing forces. However, it may not be desired in all cases to weld the sections endwise to each other or to the collars. For instance, if the sections are shrunk onto the inner pipe and are not welded together, then it is comparatively easy to remove the section of the outer pipe for replacement in case the straining openings become worn through usage. However, in the particular forms of straining elements shown in Figs. 4 and following, it is not necessary to remove the outer pipe in order to remove the straining elements, as such straining elements are insertable from the outside and may also be removed from the outside.

The constructions herein described have special advantages in that the outer casing or pipe perforations are of relatively large size and of a nature easily formed and insertable; the screening elements are easily made up in large quantities in the form of casings or by automatic machine operations; and being capable of being made by special machinery they may have any desired type or number of screening apertures.

It lies within the scope of the invention to retain the buttons in place by means other

than those shown and described herein, but the means here illustrated are preferable in that they dispense with independent holding means and call for the minimum number of operations to prepare the various elements for assembly. Thus in Figs. 4 and following where the screening elements or buttons are shown as insertable and removable from the outside of the outer pipe, the buttons are still held in place by shouldering upon the inner pipe, the buttons being held from inward displacement by the inner pipe and from outward displacement by the formation of the outer pipe now about to be described.

In Fig. 4, outer pipe perforations 14^e are of a diameter, throughout, to take the base of conical buttons 17^e. After the buttons are inserted the metal around the mouths of perforations 14^e are peened or swedged as at 14' in Fig. 5 to hold the buttons from displacement outwardly.

In Fig. 6 perforation 14^f is of substantially the same configuration as 14^d in Fig. 2, while button 17^f is bowed to such an extent that its major base may be inserted through the restricted mouth of aperture 14^f. When this base is seated on the overhanging portion 20^f of the inner pipe, as shown in dotted lines, the exposed end of the button is struck inwardly, thus expanding the button behind the overhang 14^f, as illustrated in Fig. 7.

Fig. 8 illustrates how screening elements, similar to the buttons previously described, may be inserted in the walls of the inner pipe and held from displacement by the outer pipe. Conical buttons 14^g are held from inward displacement by reason of the taper of perforations 13^g in pipe 10^g, while the portion 14^g of outer pipe 12^g that define perforations 14^g, overhangs the base of the button to hold it from outward displacement. The button may be inserted in aperture 13^g before the outer pipe is applied, or, by properly proportioning the button, it may be initially bowed, as in Fig. 6, slipped through perforation 14^g after the outer pipe is on the inner and then spread to bring its base behind portion 14^g.

Just as the buttons of Figs. 4-7 may be inserted from the outside, it will be understood they can be withdrawn to the outside. In Fig. 5 the peen at 14' may be worked up, or in Fig. 7 the button may be bowed up to its original shape (Fig. 6). And in removing worn buttons it will be understood that mutilation of the buttons is no objection.

It will be understood the drawings and description are intended only to illustrate the invention and not to limit it.

I claim:

1. In a well screen embodying a double wall casing, the two walls having registering perforations, screening elements in the perforations of the outer wall, means on the outer wall adapted to prevent outward displacement of the elements, and the inner wall being

adapted to prevent inward displacement of the elements.

2. In a well screen embodying a double wall casing, the two walls having registering perforations, screening elements in the perforations of the outer wall, means on the outer wall adapted to prevent outward displacement of the elements, and the inner wall having portions overhanging the outer wall perforations in a manner to prevent inward displacement of said elements.

3. In a well screen embodying a double wall casing, the two walls having registering perforations, screening elements in the perforations of one wall, and means on said one wall adapted to prevent displacement of the elements in one direction, the other wall being adapted to coact with the elements in a manner to prevent their displacement in the opposite direction.

4. In a well screen embodying a double walled pipe, the two walls having registering openings, the opening in one wall being larger than the opening in the other so that a shoulder is presented at the surface of the second mentioned wall, a screening element set in the opening of the first mentioned wall and shouldering against said shoulder.

5. In a well screen embodying a double walled pipe, the two walls having registering openings, the opening in one wall being larger than the opening in the other so that a shoulder is presented at the surface of the second mentioned wall, a screening element set in the opening of the first mentioned wall and shouldering against said shoulder, the opening in the first mentioned wall being larger at the end adjacent the second mentioned wall and said shoulder than it is at its other end, and the screening element fitting said opening being thereby prevented from displacement.

6. In a well screen embodying a double walled casing, the two walls having registering openings, the opening in the outer wall being larger than that in the inner wall and being substantially conical with its larger end next to the inner wall, so that the inner wall presents a shoulder at the larger end of the opening in the outer wall, and a substantially cone shaped strainer button set in the conical opening in the outer wall and shouldering against said shoulder presented by the inner wall.

In witness that I claim the foregoing I have hereunto subscribed my name this 16 day of April, 1925.

ELIHU C. WILSON.
